CLAIM

The ornamental design for countertop home water purifier, as shown and described.

DESCRIPTION

FIG. 1 is a top front perspective view of a countertop home water purifier showing our new design, on an enlarged scale;

FIG. 2 is a top plan view thereof;

FIG. 3 is a front elevational view thereof;

FIG. 4 is a rear elevational view thereof;

FIG. 5 is a bottom plan view thereof; and

FIG. 6 is a right side elevational view thereof, the left side being a mirror image.

FIG-1

FIG-2

FIG-3

FIG-4

FIG-5

FIG-6
